Primary Examiner — Steven J Czyz(74) *Attorney, Agent, or Firm* — Wilson Patent Law, LLC(57) **CLAIM**

The ornamental design for an earplug case, substantially as shown and described.

DESCRIPTION

FIG. 1 is a front perspective view of an earplug case in accordance with our new design;

FIG. 2 is a back perspective view thereof;

FIG. 3 is a front view thereof;

FIG. 4 is a back view thereof;

FIG. 5 is a right side view thereof, a left side view being a mirror image;

FIG. 6 is a top view thereof;

FIG. 7 is a bottom view thereof;

FIG. 8 is a cross section view taken along the line of 8-8 from FIG. 3 thereof; and,

FIG. 9 is a cross section view taken along the line of 9-9 from FIG. 3 thereof.

The broken lines depict portions of the article that form no part of the claimed design.
